UNITED STATES PATENT OFFICE.

CARL F. MELANDER, OF MINNEAPOLIS, MINNESOTA.

EXTENSIBLE BEDSTEAD.

977,671.

Specification of Letters Patent.

Patented Dec. 6, 1910.

Application filed March 16, 1910. Serial No. 549,594.

To all whom it may concern:

Be it known that I, CARL F. MELANDER, a citizen of the United States, residing at Minneapolis, in the county of Hennepin and State of Minnesota, have invented certain new and useful Improvements in Extensible Bedsteads; and I do hereby declare the following to be a full, clear, and exact description of the invention, such as will enable others skilled in the art to which it appertains to make and use the same.

My invention has for its object to provide an extensible bedstead of strong, durable and simple construction.

To the above ends, the invention consists of the novel devices and combinations of devices hereinafter described and defined in the claims.

In the accompanying drawings which illustrate the invention, like characters indicate like parts throughout the several views.

Referring to the drawings, Figure 1 is a plan view showing the improved bedstead; Fig. 2 is a side elevation of the improved bedstead; Fig. 3 is a transverse section taken approximately on the line $x^3 x^3$ of Fig. 2; Fig. 4 is a detail in section taken approximately on the line $x^4 x^4$ of Fig. 2, some parts being broken away; Fig. 5 is a horizontal section taken on the line $x^5 x^5$ of Fig. 4, some parts being indicated by dotted lines only; and Fig. 6 is a detail in section taken on the line $x^6 x^6$ of Fig. 2.

The head of the bedstead is made up of a pair of corner posts, 1, shown as rigidly connected by a tie bar 2. The foot member of the bedstead is shown as made up of a pair of corner posts 3 connected by a tie bar 4.

These foot and head members may, however, be of any suitable or desired design. The head and foot corner posts 1 and 3 are provided with frame-supporting devices, as shown, made up of collars 5 cast around the said corner posts and provided with projecting rest lugs 6 having transverse grooves 7.

In this improved bedstead, the spring and its frame are each made up of two parts, which constitute sections adapted to be used one in respect to the other. The head frame section is shown as made up of a pair of parallel angle iron rails 8 connected, at their front ends, by a transverse angle bar 9. The depending flange of this transverse angle bar 9 rests loosely in the notch 7 of the rest lugs 6 of the head corner posts 1. The foot

section of the spring frame is made up of a pair of parallel angle iron rails 10, which, at their rear ends, are rigidly connected by a transverse angle bar 11, the depending flange of which rests loosely in the channels 7 of the rest lug 6 of the foot corner posts. The head spring section 12 is clamped to the rails 8, preferably, by metal clamping strips 13 riveted to the sides of said rails. The 65 foot spring section 14 likewise is preferably clamped to the rails 10 by metallic strips 15 riveted thereto.

Approximately U-shaped metallic keepers or guides 16 are rigidly secured to the foot ends of the depending flanges of the rails 8 and loosely embrace the depending flanges of the rails 10. Similar but reversely applied metallic keepers or guides 17 are rigidly secured to the head ends of the depending flanges of the rails 10 and loosely embrace the depending flanges of the rails 8. The keepers 17 are rigidly secured to the ends of a transverse intermediate tie bar 18, shown as of angle iron construction. At their upper ends, legs 19 are pivotally connected by bolts or rivets 20 to the depending flange of the end portion of the tie bar 18. By reference to Fig. 3, it will be seen that these legs 19 are adapted to be turned upward into inoperative positions, indicated by dotted lines in Fig. 3, and are adapted to be turned downward into operative positions, in which positions further outward movement of said legs is prevented by the engagement of eccentric portions or shoulders 21 of said legs with the bottoms of the keepers 17. 90

The connections above described make the body or framework of the bedstead longitudinally adjustable. This adjustment is highly desirable in various places where the rooms are small and space is an important item. The bed may be adjusted according to the length of the person or persons using the same, and may be left standing in such adjustment, or it may be lengthened out at night and very materially shortened in the day time. A slight lateral adjustment, sufficient to take up the slack and compensate for the stretching of the springs, is also quite desirable, and this adjustment, as shown, is made possible by dividing the head bar 9, the foot bar 11 and the intermediate transverse tie bar 18 and adjustably connecting the sections thereof. In Fig. 3, one section of the intermediate bar 18 is shown 95

as riveted to a short angle iron section 22, and the other section of said bar 18 is adjustably connected to said bar 22 by a slot and bolt connection 23. The same means of adjustment may be applied to said bars 9 and 11.

What I claim is:

1. A bedstead having a spring frame made up of a pair of sections with their side bars constructed of angle iron, the side bars of one section adapted to slide directly upon the side bars of the other section, reversely projecting keepers for locking the side bars of one section within the side bars of the other of said sections, an intermediate tie bar connecting the inner ends of the side bar of one of said frame sections, and legs pivotally connected to said intermediate tie bar, substantially as described.
- 20 2. In a bedstead, the combination with

head and foot posts, of a spring frame supported by said posts and made up of frame sections adapted to slide one upon the other, the side rails of said frame sections, at their ends, having reversely projecting keepers 25 that embrace the side rails of the other section, an angle iron tie bar connecting the keepers of one of said frame sections, and legs pivoted to the depending flanges of said tie bar and having eccentric stop shoulders engageable with the connected keepers to limit the outward and downward movements of said legs, substantially as described.

In testimony whereof I affix my signature in presence of two witnesses.

CARL F. MELANDER.
